PROTECTIVE FUSE FOR FURNACES AND
THE LIKEPhilip H. Clark, Scotia, N. Y., assignor to General
Electric Company, a corporation of New
York

Application July 29, 1933, Serial No. 682,816

6 Claims. (Cl. 200—142)

This invention relates to fuses for furnaces and the like, and it has for its object the provision of improved means for cutting off the heat supply to the furnace upon the occurrence of a predetermined maximum temperature in the furnace.

While not limited thereto, this invention has particular application to high temperature electric furnaces, such as are used in the heat treatment of metals and the like. Such furnaces are commonly operated at temperatures of 800° F. and 900° F. and in some instances are operated at even higher temperatures.

In electrical furnaces, and also in gas and oil fired furnaces, it is desirable to protect the heating equipment from excessively high temperatures which, if they were allowed to occur, would result in damage to the heating equipment. At times, excessive temperatures can occur because of the failure of some part of the control provided for the heaters. It is also desirable to protect the work in the furnace from over heating, because excessive temperatures in some cases will absolutely ruin the material being treated. Moreover, a protection against excessive temperatures is desired in many cases for the furnace itself, especially where the furnace is constructed of materials which will not withstand overheating.

Fuses have been provided heretofore for controlling furnace heating equipment. These fuses are arranged to be exposed to the heat in the furnace, and function to shut off the heat supplied to the furnace, in the event the furnace temperature rises to a value sufficient to fuse the material of which the fuse is made.

Some difficulty has been experienced with the fuses heretofore known, because of the tendency for the fusible material to oxidize long before it is called upon to shut off the heat. This condition, of course, often results in failure of the control to shut off the heat in the event of an excessive temperature in the furnace.

In accordance with this invention, the fusible member is exposed to the heat in the furnace, and is enclosed by a casing in which is placed an enveloping atmosphere for the fusible member.

Nitrogen or some other inert gas may be used to envelope the fusible member, or the casing may be substantially evacuated of all air and gas.

I have found that the fuse arranged in accordance with this invention may be used successfully in furnaces operating at temperatures as high as 1200° F.

For a more complete understanding of this invention, reference should be had to the accompanying drawing in which Fig. 1 is an elevation

of a fuse arranged in accordance with this invention; Fig. 2 is an enlarged sectional elevation of the fuse shown in Fig. 1, parts being broken away; Fig. 3 is an enlarged horizontal sectional view of the fuse shown in Figs. 1 and 2, parts being broken away; and Fig. 4 is a diagrammatic view showing an electric furnace equipped with a protective fuse embodying this invention.

Referring to the drawing, the fuse 10 in one form of this invention comprises a fusible member 11 supported in a suitable elongated casing 12. The fusible member comprises a relatively short strip or link, as shown, formed of a suitable fusible material, such as a gold-cadmium alloy having a gold content of approximately 70%, or a gold-zinc alloy having a gold content of approximately 65%. It will be understood, of course, that other suitable alloys may be used, the selection of the alloy depending upon the temperature at which it is desired the fuse shall function to shut off the heat. The casing 12 will be made of a suitable heat resisting material, such as calorized steel, or a nickel-chromium alloy.

The fusible link 11 is supported by means of a pair of lead members 13, which in turn are supported in the casing by means of a plurality of heat refractory, electrical insulators 14.

The link 11 may be and as shown is secured to the leads 13 by compressing the leads upon the ends of the link. This may be accomplished by inserting the ends of the link into recesses provided for them in the leads, and then swaging the leads upon the link.

The members 14 may be made of any suitable refractory insulating material, such as porcelain. These members 14 are each provided with four longitudinal apertures 15, 16 and 17 and 18. The apertures 15 and 16 are positioned 180° apart and so are the apertures 17 and 18 arranged 180° apart. The two pairs of apertures comprising the apertures 15 and 16, and 17 and 18 are arranged at right angles to each other.

The apertures 15 and 16 receive a U-shaped clamping member 20 threaded through these apertures so as to hold the insulators 14 assembled in end to end relation. The insulators 14 are interlocked with each other so as to prevent relative rotative movement between them. For this purpose, each insulator is provided with a tongue 14a which is received in a groove 14b provided for it in the adjacent insulator.

The inner insulator 14, that is, the insulator shown at the extreme right of the casing 12, as viewed in the figures has a form somewhat different from the remaining insulators in that it is

provided at its inner end with a transverse groove 21 which receives the transverse central portion 22 of the U-shaped clamping member 20. It will be understood that in assembling the insulators 5 with the clamping member, the innermost insulator 14 will first be threaded upon the clamping member, and then the desired number of insulators 14 will be threaded upon the clamping member in end to end relation, as clearly shown in Fig. 10. 1. If desired, all of the insulators may be made up in the same shape as the inner insulator. This may lessen the cost of production.

The outermost insulator 14 is spaced somewhat from the next adjacent insulator to provide a 15 space 23, as clearly shown in Figs. 2 and 3, for a purpose which will be set forth hereinafter.

The leads 13 supporting the fuse 11 are threaded through the remaining pair of apertures 17 and 18 and extend completely through the abutting series 20 of insulators positioned on the right of the space 23 and terminate with their ends projecting into this space.

Suitable leads 24 are provided whereby the 25 fusible member 11 may be connected in an external electrical circuit which may be the circuit to be controlled, or a controlling circuit for the circuit to be controlled. As shown, the leads 24 are threaded through the apertures 17 and 18 provided in the outermost insulator 14, and have their 30 inner ends projecting into the space 23.

These projecting ends of the leads 24 are electrically and mechanically connected with the portions of the leads 13 projecting into the space 23 by means of sleeve-like connector members 25, 35 each of which is provided with a centrally arranged aperture 26 receiving the projecting portions of the two sets of leads. Suitable set screws 27 are threaded in the connector members and terminate in the passageways 26 so as to bear 40 against the portions of the leads which are received in the passages and thereby secure the two pairs of leads together with very good electrical and mechanical connections.

The outer ends of the leads 24 are passed to the 45 exterior of the casing 12 through suitable apertures 28 provided for them in the outer wall 12b of the casing.

The leads 24 where they emerge from the casing are surrounded by layers 30 of a suitable sealing 50 material arranged to have fluid-tight joints both with the leads 24 and with the walls of the passageways 28 surrounding these leads. As clearly shown in Fig. 3, the passageways 28 have diameters considerably larger than the diameters of the leads 24 so as to provide ample space for the sealing material 30.

The sealing layers 30 preferably will be formed of a suitable vitreous material, such as a suitable lead glass.

55 The outer ends 24a terminate in a suitable terminal box 31 where electrical connections are established with a circuit 32, which as previously indicated may be a circuit to be controlled or a controlling circuit for the circuit to be controlled. The ends 24a of the leads 24 are electrically connected with the electrical conductors 32 by means of suitable connector members 33 similar to the connector members 25.

The inner end of the casing 12 is closed by means 70 of a suitable head 34 having a fluid tight joint 35 with the casing. This joint 35 may be and preferably will be a welded joint.

75 Preferably, and as shown, the casing 12 will be formed of a plurality of detachable sections comprising the inner casing portion 12a housing the

insulators 14 and the fusible member 11, the outer head member casing 12b and an intermediate section 12c mechanically connecting the head with the casing proper 12a. Preferably, fluid-tight, screw-threaded connections will be provided between these members. 80

As previously pointed out, the casing 12 will be filled with a selected atmosphere which may be nitrogen or some other inert gas, or the casing may be substantially evacuated of air and 85 gas.

In assembling the fuse, the leads 24 will be threaded through the apertures 28 provided for them in the head 12b and the space between the leads and the walls of these apertures will be 90 filled with the glass sealing material 30. These seals may be formed by threading tubes formed of glass on the lead members and then placing the glass sleeves in the apertures 28. Then the glass sleeves are heated until softened, after 95 which pressure is applied to the ends of the sleeves so as to force the glass into intimate contact with the leads and with the walls of the passageways 28. Then the glass is allowed to cool. It has been found that this glass will firmly adhere both 100 to the leads and to these walls so as to provide fluid-tight joints both with the leads and the walls.

Then the series of insulators 14 positioned on the right of the space 23 will be assembled with 105 the U-shaped clamping member 20 by threading the insulators on the clamping member.

Then the two leads 13 with the fuse 11 attached to them will be threaded through the remaining apertures 17 and 18 of this series of insulators, and will be properly positioned with respect to the insulators so that the fuse will be supported in spaced relation with respect to the inner insulator and so that the outer ends of the leads will project from the outermost insulator 14 of this series. 110

Then the connectors 25 will be secured to the projecting portions of the leads by means of the set screws 27, after which the outermost insulator 14 will be threaded upon the clamping member 20. Then the clamping member will 120 be secured to the insulators by means of nuts 20a.

It will be observed in view of the foregoing operations that the insulators 14, the leads 13, the fusible member 11 and the connectors 25 will 125 be assembled into a unitary structure.

Then the central casing portion 12c will be threaded upon the section 12b. And then the unitary structure comprising the insulators 14, leads 13, fusible member 11 and connectors 25 will be 130 threaded upon the leads 24 so that these leads pass through the apertures 17 and 18 in the outer insulator 14, and so that the inner ends of these leads 24 project into the connectors 25. These connectors will then be secured to the projecting portions of the leads 24 by means of the set screws 27. 135

After this, the casing 12a will be slipped over the insulators and threaded to the section 12c. It will be understood that the casing 12a will be 140 sufficiently long to provide the space for the fusible member 11 when the casing is thus assembled.

In some cases, it has been found that the small amount of entrapped air in the casing may be 145 allowed to remain, the quantity not being sufficient to cause any material oxidization of the fusible member 11. The glass seals 30 at the outer end of the fuse and the seal 35 at the inner end of the casing prevent the admission of any 150

more air into the casing. However, when a fuse is to be used in very high temperature furnaces, it is advisable to exhaust the air from the casing. This air may be exhausted in any suitable manner well known in the art. If desired, the air may be exhausted and replaced with pure nitrogen, or some other suitable inert gas.

The air can be exhausted conveniently by placing a few drops of gasoline in the casing, or by placing on the casing oil or some metal, such as copper, magnesium and the like, which will consume the oxygen of the air in the casing when the fuse is heated up.

As shown, the fuse 10 is applied to an electrical-
15 ly heated furnace 37. The fuse 10 is mounted in a wall 38 of the furnace chamber, the fuse being inserted through a suitable aperture 40 provided for it in the wall so that its inner end extends into the heating chamber 41 of the furnace. In
20 other words, the fuse 10 is mounted in the wall so that the fusible member 11 is exposed to the heat in the furnace chamber.

The furnace is heated by means of a suitable heating resistance element 42 which is supplied from a suitable source of electrical supply 43. The resistance element 42 is connected with the supply source through a suitable contactor 44, the energizing coil of which is connected with the electrical supply source 43 through the fuse 10.
30 When the operating coil is energized through the fuse, the contactor is held closed so as to connect the resistance element 42 with its supply source. Under normal conditions of operation the operating coil for the contactor 44 will thus be maintained closed through the fuse so as to maintain the connections between the supply source and the resistance element. Upon the occurrence of a temperature in the furnace approaching the maximum safe temperature of
35 operation, the fusible element 11 will melt, thereby opening the energizing circuit for the operating coil of the contactor, which thereupon will permit the contactor to drop out to disconnect the resistance heating element 42.

45 In the event it is necessary to replace the fuse, the casing 12a will be unthreaded from the portion 12c, and a new fusible member 11 including the two leads 13 to which the fuse will be attached is assembled with the leads 24 in the manner previously described.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States, is:

60 1. A fuse for electric furnaces and the like comprising an elongated casing arranged to be inserted through an aperture in a furnace wall so that the inner end of said casing is exposed to the ambient temperature of the heating chamber of said furnace, an electrically insulating, heat refractory supporting member within said casing, a fusible member supported by said supporting member in said inner end of said casing so that when said casing is inserted in said aperture, said fusible member is exposed to the ambient temperature of said furnace, leads for said fusible member projecting from the outer end of said casing, means for sealing said leads where they emerge from said casing and a selected pro-

tective atmosphere within said casing about this fusible member.

2. A fuse for electric furnaces and the like comprising an elongated casing, an elongated heat refractory supporting member arranged in said casing so as to leave a space at one end of said casing, said supporting member being provided with longitudinal apertures, leads supported in said apertures projecting into said space, a fusible member within said space electrically connected with said leads and supported thereby, vitreous sealing material surrounding said leads where they enter said casing and a selected atmosphere in said casing.

3. A protective fuse for electric furnaces and the like comprising an elongated casing, a plurality of electrically insulating heat refractory supporting members in said casing in abutting relation with each other, said members having registering apertures, leads threaded in said apertures and supporting a fusible metallic member across the inner end of said members, said leads projecting from the apertures at the other end of said support and emerging from said casing, a glass sealing material surrounding said leads where they emerge from said casing and having fluid tight joints both with said leads and with said casing and a selected atmosphere in said casing.

4. A fuse for electric furnaces and the like comprising an elongated casing adapted to be inserted in an opening provided for it in a furnace wall, a plurality of heat refractory electrically insulating supporting members in said casing in abutting relation with respect to each other and arranged to leave a space in the inner end of said casing, said supporting members being provided with sets of registering apertures, a U-shaped clamping member threaded through a pair of said apertures so as to secure said supports in abutting relation, a pair of leads threaded through the other two apertures and projecting into said space at the inner end of said casing, a fusible member in said space electrically connected with said leads, and supported thereby, a pair of leads projecting from the other end of said casing, means within said casing detachably connecting said second named leads with said first named leads, layers of glass sealing material surrounding said second-named leads where they emerge from said casing and having fluid-tight joints both with said leads and said casing, and a selected atmosphere in said casing.

5. A fuse for electric furnaces and the like comprising an elongated casing adapted to be inserted through an aperture in a furnace wall, said casing comprising a pair of sections and a connection between said sections whereby they can be easily separated, a fusible member supported in the inner end of said casing so as to be exposed to the heat of said furnace when said fuse is inserted in said aperture, leads for said fusible member projecting from the opposite end of said casing, means for sealing the leads where they emerge from said casing, means within said casing detachably connecting said leads with said fusible member arranged so that said member can easily be connected with and disconnected from said leads, and a preselected atmosphere in said casing.

6. In a high temperature electric furnace, a fuse for protecting said furnace comprising an elongated casing adapted to be inserted through an aperture in a wall of said furnace, said casing comprising a pair of sections, and a connection

between said sections whereby they can be easily separated and reassembled, a fusible member within the inner end of said casing which is adapted to enter said aperture so as to be exposed to the heat of said furnace when said fuse is applied to said furnace wall, refractory supports within said casing, a pair of leads on said support electrically connected with and arranged to support said fusible member within 10 said casing, a pair of leads emerging from the other end of said casing where they are accessible

on the exterior of said furnace wall, layers of glass surrounding said leads where they emerge from said casing so as to provide fluid-tight joints between said leads and said casing, electrical connection members between said first named 80 and said second named pairs of leads arranged so that said pairs of leads can be easily connected and disconnected, and a selected atmosphere in this casing.
